UNITED STATES PATENT OFFICE.

CARL A. GEIB, OF NEW YORK, N. Y., ASSIGNOR OF ONE-HALF TO ALFRED RICHTER, OF NEW YORK, N. Y.

WINDOW-CUPBOARD.

1,387,382.

Specification of Letters Patent. Patented Aug. 9, 1921.

Application filed September 24, 1920. Serial No. 412,471.

To all whom it may concern:

Be it known that I, CARL A. GEIB, a citizen of the United States, and a resident of the Bronx, New York city, in the county of Bronx and State of New York, have invented a certain new and useful Improvement in Window-Cupboards, of which the following is a specification.

This invention relates to window boxes or cupboards, such as are adapted for extensive use in connection with popular moderately equipped apartments or dwelling houses.

Among the many objects of the invention is to provide a structure of the character indicated that may be built in a reliable and durable manner and supplied on the market at such a low cost as to make it available for use by families typifying the masses of the people, many of whom cannot afford expensive refrigerators or even ice for the preservation of milk or other food-stuffs, my new device being designed to thus take the place, to a large extent at least, of ice boxes or refrigerators.

Another object of the invention is to readily adapt a window cupboard to any width of window frame or similar building opening.

A further object is to design a window cupboard so as to make it readily applicable to a window frame, by any householder with ordinary kitchen tools such as a hammer or screw driver, and one which may thereafter be easily accessible through the window for normal household use or even lifted bodily in through the window if desired.

A still further object is to provide a cupboard of the nature set forth which comprises a relatively cheap frame having rigid sides and bottom and a lattice back, and with an open top and front, and having means in the form of a flexible apron or curtain to close all or any portion of the open front, top, or back, whereby to protect the contents of the cupboard from sunlight, rain, snow, dust, dirt, or the like objectionable conditions.

Figure 1 is a vertical section on the line 1—1 of Fig. 2.

Fig. 2 is an outside elevation, a portion of the outer cover being broken away.

Fig. 3 is a sectional detail indicating a change of position of the cover from that of Figs. 1 and 2.

Referring now more specifically to the drawings, I show my improved cupboard as

comprising a frame of any suitable size, design, construction, or material, but shown as involving a closed bottom 10 and closed sides 11 secured to the bottom. The sides or uprights 11 are beveled or inclined at their upper outer corners at 12 thereby making a better provision for the cover to shed rain or the like. At the outside or back of the frame is provided a lattice work, comprising a series of horizontal bars 13 fitted in or to the side numbers 11 parallel to one another, the series of bars extending all the way between the top and the bottom of the frame. This lattice work constitutes a means to guard the back of the cupboard and to support the cover or prevent the cover from blowing or dashing inward within the frame from the outside.

The frame may be made to substantially fill the window space or it may be of any less width. Within the frame provision is made for any suitable number of shelves such as indicated at 14 supported upon cleats 15. The shelf may be notched out as shown on 16 to accommodate any device too tall for the space between shelves. As a convenient means for securing the cupboard in the window space in a practical and reliable manner and yet enable it to be easily removed from its anchorage so as to be lifted bodily or so as to be moved inward through the window, I show pins such as nails or screws 17 driven into the window sill 18 and over which hooks or loops 19 carried by a lower portion of the inner side of the frame are directly engageable while the bottom 10 of the cupboard rests directly upon the ledge 20 at the outside of the window sill. At the sides of the cupboard are provided detachable fasteners such as hooks 21 which may be attached permanently to either the cupboard or the sides of the window frame and engageable with screw eyes in the adjacent parts. These hooks are accessible through the window opening between the sides of the cupboard and the window frame. As thus far described the cupboard may easily be put out through the window and secured in position, or as readily detached and brought within the window.

In order to close the otherwise open frame so as to protect the contents of the cupboard from dust, dirt, rain, snow, or predatory animals, I may employ a cover for either the front of the cupboard adjacent to the win-

dow, or the back of the cupboard, or both the front and the back. Such cover is shown in the form of a flexible water or weather-proof apron 22 connected at its upper edge to a bar 23 whose ends project beyond the apron for coöperation with a pair of keepers such as screw eyes 24 fixed in the upper front corners of the said members 11. The apron 22 is adapted thus to roll or drop outward 10 and downward over the top and back of the cupboard to any desired distance, and the edge of the apron remote from the bar 23 is provided with another bar 25 which may co-operate with pairs of keepers or screw eyes 26 15 at the bottom of the cupboard so as to securely fasten the apron 23 in closed position. Or the bar 25 may be adjusted so as to co-operate with other pairs of keepers at any desired elevation such as indicated at 27 at the 20 top of the frame.

The same apron 22 may if desired be dropped down in front of the cupboard directly beneath the bar 23 so as to close said front, or if desired an auxiliary apron 28 25 may be employed for this purpose. The apron 28 may constitute an extension of the apron 22 or it may be otherwise held in front

of the cupboard. These aprons constitute an effective closure for the cupboard when it is desired to make such a closure. By inserting 30 the bars or rods 23 and 25 in pockets or loops of the apron they may slip sufficiently freely to facilitate the introduction of both ends of the rods in succession into the selected keepers or eyes 24, 26, or 27.

I claim:

1. A window cupboard comprising a frame having an open top and back, a portion of the back being inclined, an opaque weather and rain proof cover for the top and back, means 40 to attach the cover to the front corners of the top, and means to secure the remote portion of the cover to another part of the frame.

2. A window cupboard comprising a frame having an open top and back, an opaque 45 weather and rain proof cover for the top and back, means to attach the cover to the front corners of the top, means to roll the cover up and down, and means to selectively secure the roll in either of a plurality of predetermined 50 positions adjacent to the top and bottom of the back.

CARL A. GEIB.
